UNITED STATES PATENT OFFICE.

PETER COOPER HEWITT, OF NEW YORK, N. Y., ASSIGNOR, BY MESNE ASSIGNMENTS, TO COOPER HEWITT ELECTRIC COMPANY, OF HOBOKEN, NEW JERSEY, A CORPORATION OF NEW JERSEY.

APPARATUS FOR OPERATING VAPOR CONVERTERS.

1,091,223.

Specification of Letters Patent. Patented Mar. 24, 1914.

Application filed April 8, 1904. Serial No. 202,191.

To all whom it may concern:

Be it known that I, PETER COOPER HEWITT, a citizen of the United States, and resident of New York, county of New York, 5 State of New York, have invented certain new and useful Improvements in Apparatus for Operating Vapor Converters, of which the following is a specification.

I have found that it is possible to operate 10 translating devices in a work circuit from a single phase source of alternating currents, with the aid of vapor converters, by deriving from a single phase source four-phase currents, utilizing two of the derived 15 currents, approximately 180° apart, for keeping the converter alive, and utilizing the other two derived currents, approximately 180° apart, for operating the translating devices. The two pairs of currents 20 approaching 90° and 270° being somewhere between 0° and 90° and 180° and 270° . The several derived currents may be produced from the same transformer, but in such cases there is apt to be difficulty due 25 to short-circuits. According to my present invention I employ two transformers, one having two secondaries for performing the operation of keeping the vapor converter alive, the other being preferably an auto- 30 transformer having a single secondary, or such an arrangement of apparatus or circuits as will give approximately the same result.

My invention will be understood by reference to the accompanying drawings, in which—

Figures 1 and 2 are diagrams of circuits adapted to the accomplishment of the purposes of my invention.

In the drawing, 1 and 2 are main conductors connected with any suitable source of single-phase alternating currents. Between the mains 1 and 2 are arranged two 40 transformers, the primary of one such transformer being shown at 3, and the other at 4. The primary 4 is brought into relation with two secondaries, 5 and 6, the arrangement 45 being such that the currents derived from the said secondaries are 180° apart. The primary 3 is provided with a secondary, 7, the natural phase difference of the currents 50 derived from the said primary and secondary being approximately 180° .

In the system thus constituted I include a

vapor converter, 8, having four positive 55 electrodes, 9, 10, 11 and 12, and a common negative electrode, 13. The working positive electrodes are those which appear at 10 and 11, the electrodes 9 and 12 being adapted to serve the purpose of keeping the converter alive.

The electrodes 9 and 12 are connected, respectively, to corresponding terminals of the transformer secondaries 5 and 6, while the negative electrode 13 is connected to an 65 intermediate point between the said secondaries by means of a wire, 14, including an inductance, 15.

Instead of using the inductance 15 in the conductor 14 an inductance may be included 70 in the circuit of the electrodes 9 and 12, respectively, as shown, for example, in Fig. 2 of the drawing at 18 and 19. When these two inductances are employed, the inductance 15 shown in Fig. 1 may be omitted. 75

The electrodes 10 and 11 are, respectively, connected with corresponding terminals of the secondary 7 and the primary 3, while the terminals of the work circuit, 16, are connected to an intermediate point between 80 the said primary and the secondary on the one hand and to the negative electrode 13 on the other. The work-circuit 16 may include any suitable device which is to be affected by currents passing through the converter 85 8, say, for instance, a storage battery, 17.

The primary 4 acting through its secondaries 5 and 6 serves to maintain current through the vapor converter 8 alternately by way of the electrodes 9 and 13 in one 90 case and 12 and 13 in the other. The function of the inductance 15 is to assist in keeping alive the converter over the zero points. At the same time the primary 3 and the secondary 7 are acting through the converter 8 to supply the translating devices in the work circuit 16. 95

In a divisional application Serial Number 241,948, filed January 20, 1905, the method of operation described herein is 100 claimed.

I claim as my invention:—

1. In a system of electrical distribution, a source of single phase alternating current, means for deriving four phase currents 105 therefrom, a direct-current work circuit, an intermediate device for applying energy from the source to the work circuit in the

- same direction at 0° and 180° , and means for deriving currents approximately 90° or 270° for causing a continuous impressed electro-motive-force in one direction.
- 5 2. In a system of electrical distribution, a vapor converter having four positive electrodes and a common negative electrode, in combination with a transformer having the terminal of its primary connected with one 10 of the positive electrodes and the negative electrode, and the respective terminals of the secondary connected with a second positive electrode and the negative electrode, a second transformer having two secondaries 15 connected with one terminal of each, respectively, to the remaining positive electrodes, and the intermediate point connected with the negative electrode.
3. In a system of electrical distribution, a 20 vapor converter having four positive electrodes and a negative electrode, in combination with a transformer having the terminals of its primary connected with one of the positive electrodes and the negative electrode, and the respective terminals of the secondary connected with a second positive electrode and the negative electrode, another transformer, having two secondaries 25
- each with one of their terminals connected, respectively, to the remaining positive electrodes, and the intermediate point connected with the negative electrode, and a work circuit interposed between the common negative electrode and an intermediate point between the primary and secondary of 30 the first named transformer.
4. The combination with a source of single-phase alternating current, of a work circuit, a converter for causing impulses of both polarities to traverse the work circuit 35 in a uniform direction, and means for transmitting current derived from the said source for maintaining the vapor converter alive, such last named means consisting of a transformer having a primary connected between the main conductors from the source and having two secondaries whose impulses are applied to the said converter.

Signed at New York, in the county of New York, and State of New York, this 50 1st day of April A. D. 1904.

PETER COOPER HEWITT.
